UNITED STATES PATENT OFFICE.

LEWIS F. KLAY, OF NIAGARA FALLS, NEW YORK.

POLISHING-MACHINE.

1,072,620.

Specification of Letters Patent. Patented Sept. 9, 1913.

Application filed April 16, 1913. Serial No. 761,454.

To all whom it may concern:

Be it known that I, LEWIS F. KLAY, a citizen of the United States, residing at Niagara Falls, in the county of Niagara and 5 State of New York, have invented new and useful Improvements in Polishing-Machines, of which the following is a specification.

This invention relates to a polishing machine which is more particularly designed 10 for polishing the tines of table forks although the same may also be used for other purposes in which like conditions exist.

It is the object of this invention to provide 15 a polishing machine for this purpose which will permit an operator to not only polish the tines of the fork without liability of cutting his hand but also permits this work to be done expeditiously and perfectly, 20 and also with infrequent renewal of the polishing surface.

My invention has the further advantage 25 in that a coarse and fine polishing effect can be produced successively upon the tines by the same machine, thereby enabling the polishing of these goods to be effected more economically.

In the accompanying drawings: Figure 1 30 is a front elevation of the polishing machine embodying my improvements. Fig. 2 is a side elevation thereof. Fig. 3 is a horizontal section, on an enlarged scale, taken in line 3—3, Fig. 1.

Similar characters of reference indicate 35 corresponding parts throughout the several views.

1 represents the main frame of the polishing machine which may be of any suitable construction and 2 a standard mounted on 40 this frame and provided at its upper ends with two bearings 3 which are arranged horizontally and transversely. In these bearings is journaled a horizontal transverse driving shaft or spindle 4 which may be 45 turned by any suitable means, for instance, by a pulley 5 secured thereto between the bearings 3, 3, as shown in Fig. 1, and adapted to receive a driving belt. At one or both ends of this shaft the same may be provided 50 with a polishing device which is constructed in accordance with my invention, only one of such devices being shown in the drawings at one end of this spindle. This polishing device comprises a rotatable supporting body 6 having the form of a wheel and preferably constructed of wood although any 55 other suitable material may be used if desired. The marginal part of this wheel is constructed in the form of two peripheral sections 7, 8 of different diameter which are 60 arranged side by side or out of line with each other in a direction lengthwise of the axis of the wheel, the peripheral section 7 of larger diameter being preferably arranged adjacent to the rear side of the wheel 65 while the peripheral section 8 of smaller diameter is arranged adjacent to the front side of the wheel. The two peripheral sections are concentric relatively to each other and to the axis of the wheel. Upon the rear 70 large peripheral section of the supporting wheel is mounted an annular flange, rim or band 9 which projects with its front edge beyond the front side of the large section of this wheel and overhangs the same. On 75 the small front section of the wheel is mounted an annular rim, flange or band 10 which projects forwardly from this wheel so as to overhang the same. The width of the rim of large diameter is such that its 80 front edge is in line with, or substantially so, with the rear edge of the annular rim of small diameter, so that both of these rims are arranged out of line relatively to each other in a direction lengthwise of the axis of 85 rotation and the outer surfaces of the same are both exposed radially. Each of these supporting rims is preferably constructed of metal which may be secured to the wheel by means of screws 11, as shown in Fig. 3, or 90 by any other suitable means. On its outer side the larger rim is provided with a polishing, abrading or buffing surface 12 and the outer side of the small supporting rim is provided with an abrading, polishing or 95 buffing surface 13. These buffing surfaces may be produced on these rims in any suitable manner, for instance, by applying to these rims a strip of cotton which is cemented to the outer side of the rim and having 100 its outer surface provided with a coating of abrasive material such as powdered emery which is attached to the cotton by means of glue or otherwise. The large supporting rim is preferably provided with a 105 polishing or abrasive surface of coarse material while the small rim is provided with a polishing or abrasive surface of fine material.

In the operation of polishing a fork 14 110 the operator engages its tines successively with the abrasive surface of the large rim,

as shown by dotted lines in Fig. 3, whereby these tines are roughly polished and any burs thereon are removed therefrom. The operator then engages the tines of the fork successively with the fine abrasive surface of the small rim, whereby all scratches or other fine marks are removed from the tines and the same is finished. While thus engaging the tines of the fork with the coarse and fine abrasive surfaces of the large and small supporting rims the fork is supported by the operator on the upper end of a stand which is arranged adjacent to the free edges of the supporting rims and horizontally in line with the axis of rotation thereof and mounted on the adjacent part of the frame. As the operator engages the tines of the fork with one or the other of the abrasive surfaces of these supporting rims he is not liable to cut his hands by reason of the fact that these rims move in fixed paths and also by reason of the fact that the small and large rims are arranged out of line relatively to each other in the direction of the axis of rotation, so that when the operator shifts the fork from the large abrasive rim to the small abrasive rim, he is not liable to get his hands cut by the large abrasive rim. When the abrasive surfaces of these rims become worn they can be very quickly and easily renewed, thereby reducing the cost of keeping the machine in repair and also effecting a saving in the cost of polishing the goods.

This machine is exceedingly simple in

construction, the same can be produced at low cost, it is not liable to get out of order and it can be operated with a small expenditure of power.

I claim as my invention:

1. A polishing machine comprising a rotatable wheel, and a plurality of annular rims or flanges arranged on said wheel and each provided with a polishing surface and arranged transversely out of line with the companion rim. 40

15 2. A polishing machine comprising a rotatable wheel, and a plurality of annular rims or flanges of different diameters arranged concentrically on the same side of the wheel and each provided with a polishing surface and the inner rim projecting forwardly beyond the adjacent outer rim. 50

20 3. A polishing machine comprising a rotatable wheel having two peripheral sections of different diameters arranged side by side in a direction lengthwise of the axis of the wheel, and rims of different diameters secured to said peripheral sections and projecting therefrom in the same direction lengthwise of the axis of the wheel and each rim being provided on its outer side with a 55 25 polishing surface. 60

Witness my hand this 14th day of April, 1913.

LEWIS F. KLAY.
